ADJUSTABLE BRACKET FOR SLIDING

TABLE TOP

Karl J. Draxler, 3231 Kelton Ave., Los Angeles, Calif.
Filed May 27, 1960, Ser. No. 32,426
6 Claims. (Cl. 311—35)

The invention relates to an adjustable bracket for a sliding table top and more particularly relates to improvements in the sliding table top construction of my Patent 2,307,396 issued January 5, 1943, in the sliding table top bracket of my Patent 2,659,641 issued November 17, 1953, and in the adjustable bracket of my Patent 2,723,891, issued November 15, 1955.

An object of the present invention is to provide a unitary bracket having an adjustable bracket arm which operates on a different principle than heretofore, and which is cheaper to manufacture.

This is accomplished by providing a unitary bracket, preferably in the form of a metal stamping, wherein the junction of the forward end of the base and the offset portion leading to the bracket arm serves as a knee or pivot point, with fastening means in the bracket adjacent the knee, and a fastening means of an adjustable height at the outer end of the base to tilt the bracket arm to an adjustable spacing with the table top to thereby accommodate sub-tops of different thicknesses while maintaining proper tolerance between the felt pad covering on the sub-top and the underside of the table top.

For further details of the invention, reference may be made to the drawings wherein FIG. 1 is a side view in elevation of a sliding table top having an array of brackets according to the present invention.

FIG. 2 is a bottom plan view on line 2—2 of FIG. 1.

FIG. 3 is an enlarged vertical sectional view through one side of the table, showing the bracket in one position of adjustment for a sub-top of certain thickness.

FIG. 4 is a view corresponding to FIG. 3 showing the bracket in another position of adjustment for a thinner sub-top.

FIG. 5 is an enlarged sectional view through line 5—5 of FIG. 4.

FIG. 6 is a perspective view of the bracket with both sets of fastening means removed.

FIG. 7 is a perspective view of the adjustable fastening means for the outer end of the base, as also shown in FIG. 5.

FIG. 8 is a sectional view on line 8—8 of FIG. 6.

Referring in detail to the drawings, the table top 1, as in my former patents, slides on a sub-top 2 mounted on a pedestal 3 or the like, having a base 4 suitably fastened by screws or the like indicated at 5.

The table top 1 is illustrated as being rectangular although other shapes may be employed. On the underside of table top 1 are arranged, centrally on each side, one or more brackets, four being shown at 6, 7, 8 and 9. In some cases, the opposite brackets like 6 and 8, as shown, may be shorter than brackets like 7 and 9, the latter being on the longer dimension of the table top 1 as shown in FIG. 6, each bracket like 6 to 9, as indicated at 10, is a metal stamping having a somewhat triangular base 11, a lateral offset 12 and an elongated bracket arm 13, and lengthwise through them is a channel, see FIG. 8. The bracket is stamped to provide an offset hollow rib or channel indicated at 14 which extends the full length of and along the middle of base 11, offset 12 and bracket arm 13.

The base 11, offset 12 and bracket arm 13 are a unitary member, having body portions extending laterally on opposite sides of raised rib 14. The body of base 11 has an extended flat surface to fit the flat under-side of the

2

table top and arm 13 has an extended flat surface to bear against the sub-top 2.

Base 11 at opposite sides thereof, has openings 15 and 16 each to receive a screw as indicated at 17, or 18, in FIGS. 3 and 4. The outer end of base 11 has a slot-like opening 19 which leads to and intersects a somewhat circular opening 20 in the raised rim or bead 21. Bead 21 has an outer sloping wall 22 and a rounded end or terminal portion 23 which defines the circular opening 20. The end 23 fits crescent shaped annular notch 24 around the head of a screw 25, providing a swivel coupling between the head of screw 25 and base 11. The sloping wall 22 provides a bearing surface for the outer half of notch 24, with end 23 having loose engagement with the inner half of notch 24 so that base 11 can tilt with respect to the axis of screw 25. When the screw 25 is screwed out, the inner half of notch 24 engages rounded end 23 to push the base 11 outwardly. Base 11 is thus forced in or out as the screw 25 is screwed in or out. The rounded end 23 is offset outwardly from the plane of base 11 by one half the height of notch 24, so that the base of the head of screw 25 is flush with the inner surface of base 11 as shown in FIG. 5, whereby the base 11 will be in contact with the table top 1 when the screw 25 is screwed all the way in the table top.

The outer end 29 of the base 11 slidably receives the notch 24 in the screw 25 whereby the outer end of base 11 is supported at a height depending on the depth to which the screw 25 is screwed into the table top, it being illustrated in FIG. 3 as screwed all the way in with the outer end 29 of base 11 flush with the underside of table top 1 whereas in FIG. 4 the outer end 29 of base 11 is separated from the table top 1 by space 36, due to the fact that screw 25 is not screwed all the way home with the result that the outer end 30 of the bracket arm in FIG. 4 is closer to the table top in the case of the thinner sub-top 31 indicated in FIG. 4. This action results from the fact that the juncture of the base 11 with the upright 12 as indicated at 37 serves as a knee or pivotal support about which the base 11 and the bracket arm 13 pivot under action of the screw 25. This pivotal action is facilitated by the loose swivel coupling between the portions 22 and 23 of the base and the notch 24 in the head of the screw 25.

The sub-top 2 or 31 has a felt pad 32 or 33 respectively glued to it as described in my former patents. In channel 14, against the inner side of offset 12 is a rubber bumper 34, to receive and cushion the edge of the sub-top.

Various modifications may be made in the invention without departing from the spirit of the following claims.

I claim:

1. A sliding table top device comprising a relatively stationary sub-top and a set of spaced brackets for the underside of the sliding table top, each of said brackets comprising a unitary metal member having a base, an offset downwardly extending from said base and a bracket arm projecting laterally from the lower end of said offset, the junction of each base with its offset acting as a pivotal support for adjusting the gap between the table top and the bracket, and each of said bases having fastening means for securing the same to the table top and including means on the outer end of the base for adjusting the spacing between the outer end of the base and the table top, to pivotally adjust the base about its said pivotal support, to thereby adjust the position of the bracket arm with respect to the table top.

2. An adjustable bracket for a sliding table top, said bracket comprising a base merging into an offset merging into a bracket arm extending offset from and substantially parallel to said base, the junction of said base with said offset acting as a pivot for adjusting the gap between the table top and said arm, said base having fastening

means adjacent said pivot for fastening said base to the table top, said base having an outer end having a rim defining a circular opening, said base having a marginal slot opening into said opening, a screw having a head fitting in said opening, said head having an annular recess embracing said rim and forming therewith a swivel coupling.

3. An adjustable bracket according to claim 2, said rim being raised and rotatably supporting said head in position with the under surface of the base of said head in substantially the same plane as under surface of said base of said bracket.

4. An adjustable bracket according to claim 2, said base, said offset and said arm being in the form of a unitary metal stamping having a hollow rib extending lengthwise therethrough.

5. An adjustable bracket according to claim 2, said base, said offset and said arm being in the form of a unitary member having a hollow rib extending lengthwise therethrough, and a resilient cushion fitting in said rib against said offset.

6. An adjustable bracket for a sliding table top, said bracket comprising a metal stamping having a base merging into an offset, and the latter merging into a bracket arm extending offset from and substantially parallel to

5 said base, said bracket arm, said offset and said base being a unitary member having a longitudinal central rib forming a channel extending lengthwise through said bracket arm, said offset and said base, said base at opposite sides thereof having apertures for fastening means adjacent said offset, said base having an outer end having a circular opening, a screw having a head having a recess rotatably fitting said opening, said base having an entrance slot admitting said head of said screw into said opening.
